UNITED STATES PATENT OFFICE.

THOMAS O. MOUNTAIN, OF EL PASO, TEXAS, ASSIGNOR TO C. W. MACE, OF EL PASO COUNTY, TEXAS.

VALVE-SPRING LIFTER.

1,269,952.

Specification of Letters Patent. Patented June 18, 1918.

Application filed February 21, 1917. Serial No. 150,176.

To all whom it may concern:

Be it known that I, THOMAS O. MOUNTAIN, a citizen of the United States, residing at El Paso, in the county of El Paso, 5 and State of Texas, have invented certain new and useful Improvements in Valve-Spring Lifters, of which the following is a specification.

This invention relates to an improved 10 valve spring lifter especially designed for use in connection with internal combustion engines and has as its primary object to provide a device of this character which may be readily engaged with the engine 15 and operated to lift any one of the intake or exhaust valve springs thereof and then adjusted for rigidly holding the said spring in elevated position so that the retaining pin or other anchor for the said spring may 20 be readily attached to or detached from the stem of the valve.

The invention has as a further object to provide a device of the above described 25 characters employing a main lever jaw adapted to engage the valve spring with the lever of the jaw operable for lifting the spring, and to further provide a second jaw adjustable upon the main jaw for supporting 30 the main jaw to hold the spring elevated.

A further object of the invention is to provide means upon the main jaw of the device for automatically locking the supporting jaw at adjustment with respect to 35 the main jaw.

And the invention has as a still further 40 object to provide an arrangement wherein the lever for the main jaw will be formed by a handle which may be detached from the said jaw so that in any instance where 45 the presence of the handle would hamper the operation of connecting the pin with the valve stem or displacing the said pin, the said handle may be readily removed.

Other and incidental objects will appear 50 as the description proceeds and in the drawings wherein I have illustrated the preferred embodiment of the invention and wherein similar reference characters designate corresponding parts throughout the several views.

Figure 1 is a side elevation showing my improved valve spring lifter in connection with a portion of a conventional type of in-

ternal combustion engine and illustrating 55 the manner in which the lifter is connected with the engine and initially engaged with the spring of one of the intake valves of the engine for lifting the spring.

Fig. 2 is a similar view illustrating the 60 supporting jaw of the device adjusted to hold the valve spring elevated.

Fig. 3 is a fragmentary top plan view of the device,

Fig. 4 is a section on the line 4—4 of 65 Fig. 3, particularly showing the mounting of the supporting jaw of the lifter and the mechanism employed for holding the said jaw at adjustment with respect to the main jaw,

Fig. 5 is a detail view of the pawl employed upon the main jaw for engagement with the rack of the supporting jaw,

Fig. 6 is a transverse sectional view on the line 6—6 of Fig. 4, particularly showing 75 the mounting of the cam slide employed upon the main jaw for actuating the pawl to release the supporting jaw, and

Fig. 7 is a detail perspective view showing the supporting jaw detached.

In carrying out the invention, my improved valve lifter is formed with a main forked lever jaw 10 having a thickened body 11 terminating in a shank 12. Arranged to coöperate with the main jaw is a forked 85 supporting jaw 13 substantially identical with the jaw 10 and provided with a squared shank or post 14 extending at substantially right angles thereto. As shown in detail in Fig. 7, the shank is formed 90 with a rack 15 upon its inner edge. The body 11 of the jaw 10 is, as particularly shown in Fig. 4, formed centrally with a suitable transversely extending opening 16, slidably receiving the shank 14 of the jaw 95 13 with the said last mentioned jaw movable to seat flat against the lower side of the jaw 10.

The shank 12 of the jaw 10 is hollow for the greater portion of its length or is cored 100 out to form a longitudinally extending recess 17 and slidably mounted in this recess is a cylindrical pawl 18 shown in detail in Fig. 5 of the drawings. This pawl, at its inner extremity, is formed with a tooth 19, 105 projecting loosely through a suitable opening in the bottom wall of the recess 17 of the shank 12 into the opening 16 for en-

gagement with the rack 15 upon the shank 14 of the jaw 13. At its opposite extremity, the pawl 18 is formed with a reduced cylindrical shank or stem 20. The shank 12 is 5 internally screw threaded adjacent the outer extremity of the recess 17 and fitted into the said recess is an externally screw threaded plug 21 having an axial opening 22 formed therethrough slidably receiving the free extremity of the shank 20 of the pawl 18 for supporting the pawl for movement longitudinally within the recess 17. Interposed between the plug 21 and the body of the pawl, is a helical spring 23 arranged 10 to surround the shank 20 of the pawl and normally urging the pawl to active position with the tooth 19 arranged to coöperate with the rack 15 upon the shank 14 of the jaw 13. In this connection, 15 it is to be observed that the plug 21 is, at its outer extremity formed with spaced sockets for receiving a spanner tool so that the plug may be adjusted longitudinally within the shank 12 for tensioning the 20 spring 23.

Formed through the body of the pawl 18 is a diametric slot 24 having a beveled or inclined inner end wall 25. Extending freely through the top of the shank 12 and 25 slidably fitting in the said slot, is a cam slide 26. This slide, at its upper extremity, is formed with a reduced neck terminating in a head or milled button 27 and, at its lower extremity, is provided with a reduced 30 cylindrical stem 28. This stem is, as particularly shown in Figs. 4 and 6, slidably fitted through a suitable opening in the lower side of the shank 12. Formed through the upper extremity of the body of the 35 slide, adjacent its forward edge, is a longitudinally extending slot 29 and fitted through the shank 12 to project freely through the said slot, is a transversely extending pin 30 connecting the slide with the said shank with the slide movable transversely through the shank. The body of the slide is, adjacent its lower extremity, formed with an inner beveled edge or cam face 31 upon the rear side thereof, arranged 40 for engagement, as particularly shown in Fig. 4 of the drawings, with the beveled or inclined inner end wall 25 of the slot 24 through the pawl 18. Consequently, when the slide 26 is moved downwardly 45 through the shank 12, the cam face 31 of the slide will act against the inclined end wall 25 of the slot for retracting the pawl against the tension of the spring 23 and withdrawing the tooth 19 from engagement 50 with the rack 15 of the shank 14 of the jaw 13. This jaw will then be permitted to drop or move away from the main jaw 10. Upon the release of the slide, the spring 23 will, of course, immediately act upon the 55 pawl to engage the pawl with the shank of

the said jaw for holding the jaw at adjustment with respect to the main jaw, the slide 30 being again forced upwardly, as will be readily understood, upon the outward movement of the pawl under the influence 70 of the said spring. In this connection, it should be noted that the tension of the spring 23 will be sufficient to overcome the weight of the jaw 13 upon the tooth 19 of the pawl so that the said jaw may be positioned against the jaw 10, as illustrated in Fig. 4, and held in such position by the said pawl.

Arranged to coöperate with the main jaw 10 is a lever or handle 32 formed, at its 80 inner extremity, with a reduced extension 33 threaded into the outer internally threaded extremity of the shank 12 of the said jaw. The handle may thus be easily disconnected from the jaw 10 and is preferably milled adjacent its outer extremity, as particularly shown in Figs. 1 and 2, so that the handle may be readily grasped. Slidably fitted upon the handle is a fulcrum or sleeve 33 provided at one side with 85 a set screw 34 for holding the sleeve at adjustment longitudinally of the handle. Formed on the sleeve, is a hook 35 and detachably connected to the said hook, is one end of a chain or other suitable flexible element 36. Detachably connected to the opposite extremity of the said chain, is a hook 37 providing a suspension device for the fulcrum sleeve of the handle adjustably connected with the said sleeve by the chain 36. 100

In order that the operation of my improved valve spring lifter may be accurately understood, I have, in Figs. 1 and 2 of the drawings, shown the device in connection with an intake valve of a conventional type of internal combustion engine. One of the cylinders of the engine is shown at 38 and projecting downwardly through the overhanging portion of this cylinder is a valve stem 39, with which is arranged to 105 coöperate a push rod 40 mounted in the usual guide 41. Surrounding the valve stem is a valve spring 42 which, at its lower extremity, is received by a collar 43. Formed through the valve stem, adjacent 110 its lower extremity, is an opening 44 adapted to receive a pin for retaining the spring upon the valve stem.

The present invention is, as previously intimated, designed to provide a device for 120 compressing the spring 42 so that the said pin may be readily placed in or removed from the opening 44 in the valve stem. In using the device, the hook 37 is first engaged over the head of the cylinder 38 or 125 is engaged with some other suitable portion of the engine above the valve when the chain 36 is adjusted to support the handle 32 in an upwardly inclined position with the main jaw 10 of the device engaging 130

around the valve stem 39 beneath the collar 43, the supporting jaw 13 being seated against the jaw 10, as illustrated. The sleeve 33 thus supports the handle to provide a lever with the sleeve shiftable longitudinally of the handle to adjust the fulcrum point of the said lever. With the device thus attached, the outer extremity of the handle 32 may be moved downwardly for lifting the valve spring 42, as illustrated in Fig. 2. Upon the lifting of the said spring, the slide 26 is then actuated to release the jaw 13 when this jaw will drop to engage around the guide 41 of the push rod with the pawl 18 coacting with the ratchet 15 upon the shank 14 of the said jaw for holding the jaw at adjustment with respect to the main jaw 10 to support the said spring in elevated position. With the spring thus elevated, the retaining pin for the spring may be readily fitted through or displaced from the opening 44 in the valve stem for either connecting the spring with the valve or detaching the spring therefrom. In like manner, any other conventional anchor or retainer for the spring may be attached to or detached from the valve stem. Since, as illustrated in Fig. 2, the jaw 13 will, when adjusted with respect to the main jaw to seat against the push rod guide or other adjacent portion of the engine, receive the full load upon the main jaw, the hook 37 may be detached from the engine and the handle 32 disconnected from the main jaw so that access to the valve stem will be unhampered.

It will, therefore, be seen that I provide a particularly simple and efficient construction for the purpose set forth and a device which may be readily used in connection with substantially any conventional type of internal combustion engine having intake and exhaust valves of the character herein set forth.

Having thus described the invention, what is claimed as new is:

1. A device of the character described including a main jaw, means for pivotally supporting the said jaw suspended, and a second jaw adjustable with respect to the main jaw independently of said first-mentioned means for supporting the main jaw under the weight of a load.

2. A device of the character described including a main jaw, flexible means adjustable for pivotally supporting the jaw, and a second jaw adjustable with respect to the main jaw for supporting the main jaw in position sustaining a load.

3. A device of the character described including a main jaw, a supporting jaw carried thereby and slidably connected with the main jaw, means for pivotally supporting both of the said jaws suspended to provide a fulcrum for the main jaw, and

means for locking the supporting jaw at adjustment with respect to the main jaw to sustain the main jaw under the weight of a load.

4. A device of the character described including a main jaw provided with a recessed shank, a supporting jaw having a shank slidable upon the main jaw, a pawl mounted in said recess and normally arranged to engage the shank of the supporting jaw with the said supporting jaw adjustable laterally with respect to the main jaw, and means arranged at an angle to the axis of the pawl and slidably connected to the shank of the main jaw for retracting said pawl.

5. A device of the character described including a main jaw provided with a hollow shank, a supporting jaw adjustable with respect to the main jaw and having a shank slidably connected with the said main jaw, a pawl slidably mounted in the shank of the main jaw, a plug in said main jaw shank, a spring bearing between the pawl and said plug and normally urging the pawl to cooperate with the shank of the supporting jaw for holding the said jaw at adjustment with respect to the main jaw, and means upon the shank of the main jaw for retracting the said pawl.

6. A device of the character described including a main jaw having a hollow shank, a supporting jaw adjustable with respect to the main jaw and having a shank slidably connected therewith, a pawl slidably mounted in the shank of the main jaw, a plug adjustable in said main jaw shank, yieldable means bearing between the said plug and the pawl and normally urging the pawl to cooperate with the shank of the supporting jaw for holding said supporting jaw at adjustment, the plug being movable within the shank of the main jaw for tensioning the said yieldable means, and means upon the main jaw for retracting the said pawl.

7. A device of the character described including a main jaw having a hollow shank, a supporting jaw adjustable with respect to the main jaw and having a shank slidably connected therewith, a pawl slidable in the shank of the main jaw and provided with a stem, a plug within the said main jaw shank slidably receiving said stem for guiding the pawl within the shank of the main jaw, yieldable means bearing between the plug and said pawl and normally urging the pawl to cooperate with the shank of the supporting jaw for holding the supporting jaw at adjustment, and means upon the shank of the main jaw for retracting the said pawl.

8. A device of the character described including a main jaw having a hollow shank, a supporting jaw adjustable with respect to the main jaw and having a shank slidably

connected therewith, a pawl within the shank of the main jaw and having a slot formed therethrough provided with an inclined wall, means normally urging the pawl to coöperate with the shank of the supporting jaw for holding the said jaw at adjustment, and a slide freely connected to the shank of the main jaw and projecting into said slot for engagement with the said inclined wall thereof with the slide reciprocable for retracting the said pawl.

9. A device of the character described including a main jaw having a hollow shank, a supporting jaw adjustable with respect to the main jaw and having a shank slidably connected therewith, a pawl slidable within the shank of the main jaw, means normally urging the pawl to coöperate with the shank of the supporting jaw for holding the supporting jaw at adjustment, and a slide freely connected to the shank of the main jaw and formed to coöperate with the pawl with the said slide reciprocable for retracting the said pawl.

10. A device of the character described including a main jaw having a hollow shank, a supporting jaw adjustable with respect to the main jaw and having a shank slidably connected therewith, a pawl slidable in the shank of the main jaw, a guide mounted in the said shank and co-acting with the pawl for supporting the said pawl in its sliding movement, means bearing between the said guide and the pawl and normally urging the pawl to coöperate with the shank of the supporting jaw for holding the supporting jaw at adjustment, and means upon the

shank of the main jaw for retracting the said pawl.

11. A device of the character described including a main jaw provided with a recessed shank, a supporting jaw adjustable with respect to the main jaw and having a shank slidably connected therewith, a pawl mounted in the recess of said shank, yieldable means associated with the said pawl normally urging the pawl to engage the shank of the supporting jaw for holding the supporting jaw at adjustment, and means slidably connected to the shank of the main jaw and formed to co-act with the pawl with the said means reciprocable for retracting the pawl and adapted to be projected to normal position by the tension of the said yieldable means upon the pawl.

12. A device of the character described including a main jaw provided with a shank, a supporting jaw adjustable with respect to the main jaw and provided with a shank slidably connected therewith, a pawl carried by the main jaw shank, means normally urging the pawl to co-act with the said supporting jaw shank for holding the supporting jaw at adjustment, a slotted slide mounted upon the shank of the main jaw and formed to co-act with the pawl, a stem formed on said slide and freely engaging with the main jaw shank for directing the slide in its movement, and a pin fitted through the slot in the slide and freely connecting the slide to the said main jaw shank with the slide reciprocable for retracting the pawl.

In testimony whereof I affix my signature.
THOMAS O. MOUNTAIN. [L. s.]
